UNITED STATES PATENT OFFICE.

KAY H. HOFFMAN, OF WINTHROP, MARYLAND.

BOTTLE-STOPPER.

1,031,446.

Specification of Letters Patent.

Patented July 2, 1912.

Application filed January 12, 1912. Serial No. 670,829.

To all whom it may concern:

Be it known that I, KAY H. HOFFMAN, subject of the King of Denmark, residing at Winthrop, in the county of Charles and 5 State of Maryland, have invented certain new and useful Improvements in Bottle-Stoppers, of which the following is a specification.

This invention relates to bottle stoppers, 10 and has as its object to provide a stopper which may be readily and quickly applied within the neck of the bottle and will close the bottle in an air tight and liquid tight manner.

15 A further aim of the invention is to provide a stopper which, while adapted to completely seal the bottle within the neck of which it is positioned, may be readily removed without the necessity of using an 20 opener.

25 A further object of the invention is to provide a bottle stopper which will not be corroded by acids and which will not in any way affect the taste of the contents of 25 the bottle.

Another object of the invention is to provide a stopper so formed that when inserted into the neck of a bottle, a space will be left between the stopper and the inner 30 side of the neck of the bottle above the stopper to receive sealing material of any kind, should this be found necessary or desirable.

The invention aims further to provide a 35 stopper of the type mentioned which will be particularly adapted for use in sealing bottles containing carbonated or brewed beverages, such as beer, etc.

Another object of the invention is to provide a bottle stopper which will be but little, if any more expensive to manufacture than the ordinary crown cap now in use, and which may be repeatedly used and may be manufactured from one piece and one 45 kind of material.

For a full understanding of the invention reference is to be had to the following description and accompanying drawing, in which:

50 Figure 1 is a vertical sectional view through the stopper embodying the present invention and through the neck of the bottle within which the stopper is fitted. Fig. 2 is a view in elevation of one form of stopper removed from the bottle neck. Fig. 3 is a

view similar to Fig. 1 illustrating a slight modification of the invention. Fig. 4 is a similar view illustrating another modification. Figs. 5 and 6 are views illustrating the stopper applied within the neck of an 60 ordinary bottle, such for example, as a beer bottle.

In the drawing, the stopper embodying the present invention is illustrated as comprising a substantially conical body 1 provided at its base with an outstanding circumscribing flange 2. At its upper end the body 1 is provided with a stem 3 which may be grasped between the fingers for the purpose of removing the stopper from a bottle 70 in a manner to be presently explained. The base of the body 1 of the stopper is under normal conditions flat or plane. The stopper is preferably formed from rubber and possesses the required degree of elasticity to 75 allow for compression of its flange 2 and the base portion of the body 1.

The bottle neck shown in Fig. 1 is indicated by the numeral 4 and at its upper end is exteriorly tapered as at 5, and the said 80 neck is formed interiorly with an annular groove 6 having a bottom wall 7 which is slightly rounded as at 8, and an inclined wall 9. The bottom wall 7 of the groove forms an annular shoulder and except for its 85 rounded portion 8, lies in a substantially horizontal plane. The wall 9 of the groove is concentric with respect to the wall 5, as shown in the said Fig. 1 and overhangs the wall 7. 90

In applying the stopper to the bottle neck shown in Fig. 1, a machine or tool is employed which includes a plunger, preferably of hard oak, as shown in the said Fig. 1 and indicated by the numeral 10, this plunger having a tapered neck 11 and an axially located socket 12 which opens through the lower end of the said neck. The neck 11 is of a diameter less than or equal to the internal diameter of the bottle neck, and the socket 12 is of a diameter to receive the stem 3 of the stopper and in this instance receives the said stopper stem frictionally. The stem of the stopper shown in Fig. 1, as well as that shown in Figs. 4 and 5 is increased in diameter from its lower end to a point substantially midway between its ends above which point it is of conical form, the first mentioned portion being indicated by the numeral 3^a and the 100 105 110

conical portion by the numeral 3^b. The stem is of course of greater diameter at the point of juncture of the portions 3^a and 3^b than at any other point in its length, and it is at this point that it is frictionally engaged by the walls of the socket 12 of the plunger. Prior to the operation of the plunger to force the stopper into the bottle neck, the stem 3 of the stopper is received 5 in the socket 12 and the base of the stopper rests upon the upper end of the neck of the bottle. With the stopper in this position, the plunger 10 is forced downwardly thereby forcing the stopper into the bottle neck 10 until the stopper assumes about the position shown in Fig. 1 in dotted lines. The plunger 10 is then quickly retracted so as to draw upwardly upon the stem of the stopper and cause the rim and flange 2 to fit 15 snugly in the corner between the angle of the groove 6 and upon the wall 7, as illustrated in Fig. 1 of the drawing. An advantage gained by forming the upper end of the stem 3 of the stopper of conical form 20 resides in the fact that should the stem be out of axial alinement with the plunger when the plunger descends, the stem will be guided into the socket 12 of the plunger. 25

The stopper at the rim of its flange 2 and 30 at the base of its body 1 is of a diameter greater than is the bottle neck interiorly so that when the stopper is drawn upwardly to assume the position as shown in full lines in Fig. 1 the flange 2 and the base portion 1 will be compressed and the under side of the base portion will then be concaved, as indicated at 13 in the said Fig. 1. When thus 35 assembled with the bottle neck, the stem 3 of the stopper will project above the upper 40 end of the bottle neck so that it may be readily grasped between the fingers and a pull exerted thereon to remove the stopper. It will be understood however, that the walls of the socket 12 do not so tightly engage or 45 fit the stem 3 as to pull the stopper upwardly beyond the full line position, as shown in Fig. 1. It will also be understood that any pressure created within the bottle will tend to more firmly force the flange 2 and base 50 portion of the body 1 of the stopper against the wall 9 of the groove in the bottle neck, and that due to the fact that the body of the stopper is relatively thin at its base portion, pressure against the under side of the stopper will cause the base portion to bear more firmly against the wall 9 of the groove, although when a pull is exerted upon the stem 3 the tendency will be to contract or decrease 55 the diameter of the said base portion. As a result, less resistance will be offered to removal of the stopper when a pull is exerted upon its stem 3 than when pressure is exerted against its under side. Under certain 60 conditions it may be desirable to employ a stopper of the form shown in Fig. 2, this 65

stopper having an ellipsoidal stem which at its greatest diameter is of a size to be freely received in the socket of the plunger.

The bottle neck shown in Fig. 3 is formed interiorly with a groove 14 having an upper 70 wall 15 and a wall 16, this groove corresponding in the general location of its walls to the groove 6, except that in the instance of the form of the invention shown in Fig. 3, the wall 15 overhangs the wall 16. In fitting the stopper shown in Fig. 2 into the neck of the bottle shown in Fig. 3, the method above described is carried out. However, as above stated, the stem of the stopper shown in Fig. 2 at its widest part 80 is of a diameter less than the diameter of the socket 12 so that when the plunger is retracted the stopper will be left in the condition shown in the said Fig. 3, its stem not being frictionally engaged by the walls of 85 the socket.

The bottle neck shown in Fig. 4 and indicated by the numeral 17 is formed interiorly with an annular groove having an upwardly, 90 inwardly inclined bottom wall 18, a substantially vertical wall 19, and an upwardly, inwardly inclined upper wall 20 which overhangs the wall 18 and is inclined at a greater angle than the said wall 18. The stopper shown in Fig. 1 is assembled with the bottle 95 neck 17 in precisely the same manner as it is with the bottle neck 4 and will assume the position shown in dotted lines in Fig. 4 when the plunger descends, and the position shown in full lines in the said figure when 100 the plunger is retracted.

By referring to Figs. 5 and 6 of the drawing, it will be observed that the stopper may be readily applied within the neck of an ordinary beer bottle, or the like. 105

In Fig. 5, the stopper illustrated is of the form shown in Figs. 1 and 4 and in fitting the stopper within the neck of such a bottle, the operation described in connection with the fitting of the stopper to the bottle necks 110 shown in the said Figs. 1 and 4 is carried out, in which event the stopper will assume the position shown in the said Fig. 5, upon retraction of the plunger. The stopper shown in Fig. 2 is employed in sealing the 115 bottle neck shown in Fig. 6 and the manner of fitting this stopper to this form of the bottle neck is the same as in fitting the stopper shown in Fig. 3. When fitted as shown in Fig. 6, it is well adapted to seal a bottle 120 containing a carbonated or brewed beverage, inasmuch as pressure against its under side when so fitted will tend to force its base and flange against the wall of the neck much more firmly than when fitted as shown in 125 Fig. 5. By referring to Figs. 1, 3, 4, 5 and 6, it will be observed that in every instance there is a space left between the stopper and the inner surface of the bottle neck above the base of the stopper into which space may 130

be poured paraffin, sealing wax, or in fact any other suitable sealing material, if it is found expedient.

Having thus described the invention what is claimed as new is:—

1. A bottle stopper comprising a compressible body, and a stem projecting from the upper side of the body, the stem being increased in diameter from its lower end to a point between its ends and above the said point being of conical form.

2. A bottle stopper of compressible material having a conical body relatively thin at and adjacent the periphery of its base, and a stem forming a continuation of the upper end of the body.

3. A bottle stopper consisting of a one piece body having a stem projecting from its upper side, the body being circular at its

base and being gradually increased in thickness from the periphery of its base to its point of juncture with its stem, the said stopper being of compressible material.

4. A bottle stopper of compressible and elastic material comprising a substantially conical body having a stem projecting from its apex and provided at its base with an integral flange capable of being flexed to surround the body or to project from the under side of the body whereby to provide the body with a convex or concave under side.

In testimony whereof, I affix my signature in presence of two witnesses.
